UNITED STATES PATENT OFFICE.

JOHN J. KENNEDY, OF BRANFORD, CONNECTICUT.

DESIGN FOR THE ORNAMENTATION OF HARDWARE.

SPECIFICATION forming part of Design No. 14,536, dated January 8, 1884.

Application filed November 10, 1883. Term of patent 7 years.

To all whom it may concern:

Be it known that I, JOHN J. KENNEDY, of Branford, in the county of New Haven and State of Connecticut, have invented a new Design for the Ornamentation of Hardware; and I do hereby declare the following, when taken in connection with accompanying drawing and the letters of reference marked thereon, to be a full, clear, and exact description of the 10 same, and which said drawing constitutes part of this specification, and represents a face view of a hinge, the ground showing the characteristic feature of the design.

This invention relates to a design for the ornamentation of hardware—such as butts, escutcheons, lock-fronts, knobs, bell-pulls, &c.—and in which the ornamentation is made to correspond, so that all of the hardware in an apartment or building may present the same 20 general style or pattern, and in illustrating the design I show a butt-hinge, which will be sufficient to show the many articles to which it is applicable; and the design consists in the representation of ivy-leaves, the surface between the leaves matted. This representation of ivy-leaves and matted surface forms a ground 25 upon which bars, beads, or other ornamentation may be placed in relief, the design relat-

ing only to the ground upon which such relief ornaments are arranged, this ground giving 30 to the article its characteristic feature. The articles are usually provided with a plain border to form a panel. The surface of the panel shows the representation of ivy-leaves and a roughened or matted surface between the 35 leaves, as shown in the accompanying illustration. This surface forms a ground upon which any desired ornamentation may be placed in relief, such relief ornamentation depending upon the shape of the article, and constituting no part of this design, it being understood 40 that it is the ground only that constitutes the characteristic or essential feature of this design.

I claim—

The herein-described design for the ornamentation of hardware, consisting of the ground upon which is the representation of ivy-leaves, the surface between the leaves roughened or matted, as shown in the accompanying illustration. 50

JOHN J. KENNEDY.
